DESIGN FOR A ROLLING PLUG BAIT

Hans P. Olson, Racine, Wis.

Application May 29, 1944, Serial No. 113,777

Term of patent 14 years

(CL. D31—4)

To all whom it may concern:

Be it known that I, Hans P. Olson, a citizen of the United States and resident of Racine, in the county of Racine and State of Wisconsin, have invented a new, original, and ornamental Design for a Rolling Plug Bait, of which the following is a specification, reference being had to the accompanying drawing, forming part thereof.

Figure 1 is a side elevational view of a rolling plug bait showing my new design.

Figure 2 a plan view of the same.

Figure 3 a rear view.

Figure 4 a front view of the bait.

Figure 5 a cross section of the same indicated on line 5, 5 of Figure 1.

I claim:

The ornamental design for a rolling plug bait, as shown,

HANS P. OLSON,
